INCOME TOTALIZING DEVICE

Herman G. Jensen and Harry H. Bostrom, Chicago, Ill., assignors to The Seeburg Corporation, Chicago, Ill., a corporation of Delaware

Filed June 14, 1965, Ser. No. 469,032

17 Claims. (Cl. 235—100)

This application is a continuation-in-part of application Ser. No. 286,081, filed June 6, 1963, now abandoned.

This invention relates to an income totalizing device and more particularly to apparatus for cumulatively totalizing in incremental amounts the value of credits established in a credit responsive mechanism and for recording the totalized values (as on a counter meter or on a permanent recording form).

When a vending machine is installed in a given location, the coins which accumulate therein must be periodically removed. Typically, the coin removal is performed by a route man who services a multiplicity of machines. It is obviously desirable that an accurate and independent system be established to record the value of the coins received in a given machine.

With a cumulative recorder of coin values, one is able to determine the total amount of the coins received in a machine as well as the incremental amount (by subtraction) received since the last emptying of the cash box. This information not only impedes theft of the receipts but also serves to indicate quickly and reliably how well a given machine is performing in terms of cash accumulated. The performance indication is useful both with respect to the vending of products and of services and is particularly desirable when an intangible service is dispensed by machine, as, for example, a typical coin-operated phonograph installation, or a coin-operated washing or cleaning machine.

The subject invention comprises an electro-mechanical device of the advancing ratchet gear type for indicating the cumulative total value of credits which have been established in a credit responsive mechanism. In the described embodiment, cumulative total values of coins of nickel, dime, quarter, and half-dollar denominations are recorded upon deposit thereof in a coin sensitive mechanism. The device utilizes an advancing ratchet gear wheel and a pawl actuator which are mounted in a frame housing for rotation with respect to a fixed shaft. Means including the pawl actuator are provided for rotating the ratchet gear wheel by a predetermined degree of angular displacement in response to a coin signal determined by the value of an inserted coin and for transforming the angular displacement of the ratchet wheel into a gear movement which correspondingly registers a money value incremental change on a conventional gear counter mechanism.

In the preferred embodiment of the invention herein-after described, the pawl actuator is reciprocably rotated from a given rest position by solenoid actuated crank means corresponding to the indicated coin values. On the reverse or return stroke of the pawl actuator, an escapement pawl mechanism (comprising advancing pawl means for rotating the ratchet gear wheel in a given direction and locking pawl means for preventing rotation of the ratchet gear wheel in the opposite direction) actuates the ratchet gear wheel for rotation by a first amount; an amount twice the first said amount; an amount five times the first said amount; and an amount ten times the first said amount in accordance with a nickel, dime, quarter, or half-dollar respective coin signal. As a further feature, adjustable stop means are positioned in the path of movement of the pawl actuator in order to determine the said given rest position and in order to

2

terminate the return rotation of the pawl actuator to the said rest position after the described reciprocable rotation of the pawl actuator by means of the solenoid actuated crank means.

It is an object of this invention to provide for the cumulation and recordation of coin values inserted into a coin-receiving mechanism by a unique income totalizing system which is compact, inexpensive, reliable, accurate, and essentially tamper-proof.

It is a further object of this invention to provide an income totalizing system which may be utilized for income evaluations in any one of a variety of currencies, both domestic and foreign, and in fact which may be readily converted by a simple substitution of redimensioned parts for use with one or the other of such currencies.

It is a still further object of this invention to provide a simple system for coin value cumulation in incremental amounts by a solenoid actuation of a one-way rotation ratchet gear wheel which is ordinarily situated in a given rest position and which is rotated from that position in discrete steps correspondingly to a coin value signal sensed by appropriate solenoid means.

These and other objects, advantages, and features of the subject invention will hereinafter appear, and, for purposes of illustration, but not of limitation, an exemplary embodiment of the subject invention is shown in the appended drawings, in which:

FIGURE 1 is a top plan view of the income totalizing device, as mounted in a tamper-proof receptacle, the cover of which is removed for clarity;

FIGURE 2 is an inverted rear view, taken along the line 2—2 of FIGURE 1;

FIGURE 3 is an inverted side elevational view with a side wall partially removed for clarity, taken along the line 3—3 of FIGURE 1;

FIGURE 4 is a sectional view taken along the line 4—4 of FIGURE 2;

FIGURE 5 is a front view of the device shown in FIGURE 1; and

FIGURE 6 is an inverted sectional view taken along the line 6—6 of FIGURE 5.

With reference to the drawings, the numeral 1 generally designates an income totalizing device produced in accordance with the subject invention. The device 1 comprises a base plate 10 which is adapted to cooperate with a cover box (not shown) in order to form a completely enclosed and tamper-proof receptacle. A conventional lock assembly 9 (see FIGURE 1) engages an appropriate insertion member of the said cover box in order to effectuate the desired closure. Side walls 11 and 13 extend perpendicularly from the base plate 10 and are affixed thereto by conventional means, such as by bolt assemblies generally indicated by the reference letter

55 B. Similarly, an intermediate wall 12 extends perpendicularly from the base plate 10 and is affixed thereto. The intermediate wall 12 is positioned intermediate the side walls 11 and 13 and relatively closer to the side wall 11, as shown in FIGURES 2 and 5. A front top plate 14 and a rear top plate 15 bridge the respective walls 11, 12, and 13, as indicated in FIGURE 1. Upper and lower L-flanges 16 and 17 respectively are affixed to the side wall 11. Switch circuitry, generally designated by the reference numeral 18, is mounted intermediate the flanges

60 16 and 17 for cooperation with the income totalizing device 1. However, the circuitry as such does not form a part of the instant invention and accordingly is not described or illustrated in detail. The said circuitry 18 connects with a front terminal board 19 (see FIGURE 2)

65 and with a rear terminal board 20 (see FIGURE 5) in order to effectuate certain electrical signals. A cable aper-

ture 21 is provided in the base plate 10, and electrical leads generally designated by the reference letter W pass through the aperture 21 in order to send and receive signals from the circuitry 18. The said leads extend into the volume defined between the walls 11 and 12, but are not illustrated in order to promote clarity. A switch mounting plate 8 (fragments of which are shown in FIGURE 5) is mounted between the intermediate wall 12 and the side wall 13. Nickel, dime, quarter, and half-dollar switches indicated respectively by the reference characters N, D, Q, and H are affixed to the plate 8 (as schematically indicated in FIGURE 5) for a purpose hereinafter described.

An L-flange 22 (see FIGURE 5) is affixed to the intermediate wall 12 on the side thereof facing the side wall 13. The flange 22 supports a counter housing 23, which contains a conventional counter barrel assembly 26. The assembly 26 is mounted on a counter shaft 24, and a pinion gear 25 is affixed to an exposed end of the counter shaft 24. A window 27 is provided in the counter housing 23 such that, in a conventional manner, rotation of the pinion gear 25 will cause appropriate indicia to be placed beneath the window 27 such that the cumulative total of revolutions of the pinion gear 25 may be expressed in any desired system (e.g., cumulative dollars and cents).

A fixed shaft 30 is mounted between the intermediate wall 12 and the side wall 13. A ratchet gear 31 is mounted for rotation on the shaft 30, and a spur gear 32 is likewise mounted for rotation on the shaft 30 adjacent to ratchet gear 31. The ratchet gear 31 and the spur gear 32 may be connected, or, as best seen in FIGURE 4, the said gears 31 and 32 may be a one-piece integral construction such as a molded plastic part. As best shown in FIGURE 5, the pinion gear 25 intermeshes with the spur gear 32 such that rotation of the spur gear 32 causes a corresponding rotation of the pinion gear 25.

A bifurcated pawl actuator 33 is also mounted for rotation on the shaft 30. The pawl actuator 33 is provided with two parallelly extending legs 34 and 35, each of which has a suitable aperture for receiving the shaft 30 therethrough. A shaft 36 is mounted between the legs 34 and 35 adjacent to the base of the pawl actuator 33. An advancing pawl 37 is rotatably mounted on the shaft 36, and a spring 38 normally urges the advancing pawl 37 into engagement with the teeth of the ratchet gear 31.

The base of the pawl actuator 33 is provided with an off-set (see FIGURES 4-6) such that the lowermost portion of the leg 35 adjacent the base of pawl actuator 33 is recessed inwardly (relative to the FIGURE 5 disposition) to define an abutment shoulder 39, as compared to the corresponding lowermost portion of the leg 34 which defines an abutment shoulder 41. The base of the pawl actuator 33 is also provided with a recess 40 (see FIGURE 3) on the side thereof corresponding to the leg 34. The recess 40 defines an abutment shoulder 42 (see FIGURE 3) in line with the upwardly extending leg 34 of the pawl actuator 33. Lever arms 44 and 45 extend outwardly in a generally perpendicular fashion from the respective legs 34 and 35 of the pawl actuator 33.

Four crank lever members (corresponding respectively to four designated coin denominations, such as nickels, dimes, quarters, and half-dollars) are mounted for rotation on the shaft 30, two on either side of the ratchet gear 31 and spur gear 32. As shown in the drawings, these crank levers are the nickel lever 46, the dime lever 47, the quarter lever 48, and the half-dollar lever 49, with the nickel and quarter levers 46 and 48 respectively being mounted closest to the side wall 13 and with the dime and half-dollar levers 47 and 49 respectively being mounted closest to the intermediate wall 12. Collar spacing members 50, 51, 52, and 53 are also mounted on the shaft 30, and retaining rings, generally designated by the reference letter R, serve, in conjunction with the collar spacing members 50-53, to maintain the levers 46-49 and

the legs 34 and 35 of the pawl actuator 33 separate from each other and from the ratchet gear 31 and spur gear 32. Four solenoids corresponding to each of the levers 46-49 are mounted within the framework defined by the base plate 10, the intermediate wall 12, the side wall 13, and the top cover plates 14 and 15. These solenoids are momentarily actuated by the reception of deposited coins of varying denominations in a suitable coin chute (not shown), such that the deposit of a coin will be electro-mechanically transformed by the device 1 into a cumulatively registered coin value, as indicated by rotation of the counter barrel assembly 26. The said four solenoids are designated as follows: the nickel, dime, quarter, and half-dollar solenoids are indicated respectively by the reference numerals 54, 55, 56, and 57. Likewise, the respective plungers of the said solenoids are indicated by the designations 54P-57P.

The plunger 54P of the nickel solenoid 54 is attached to the nickel lever 46 by an actuating spring 60. Similarly, the plunger 55P of the dime solenoid 55 is connected to the dime lever 47 by an actuating spring 59. The plunger 56P of the quarter solenoid 56 is connected to the quarter lever 48 by a connecting link 56L (see FIGURE 3), and similarly the plunger 57P of the half-dollar solenoid 57 is connected to the half-dollar lever 49 by a connecting link 57L. A spring 62 (see FIGURE 3) and a spring 63 (see FIGURE 6) normally urge the respective nickel and dime levers 46 and 47 to the respective positions shown in FIGURES 3 and 6 (that is, the full line position for the lever 46 shown in FIGURE 3). The springs 62 and 63 are affixed to a locking pawl housing 64, hereinafter described. Springs 58 and 61, which are illustrated in FIGURE 4, similarly are connected to the respective levers 49 and 48 so as to normally urge these levers to the respective dispositions shown in FIGURES 3 and 6 (again, the full line position for the lever 48 shown in FIGURE 3). The springs 58 and 61 are affixed to the cover plate 14 (as shown in FIGURE 1).

A locking pawl housing 64 is affixed to the base plate 10 beneath the shaft 30 and between the solenoids 56 and 57. The housing 64 is generally hollow, and a shaft 65 passes through the opposite walls thereof (see FIGURE 2). A locking pawl 66 is mounted on the shaft 65, and a spring 67 normally urges the locking pawl into engagement with the teeth of the ratchet gear 31. As hereinafter described, the combined interaction of the advancing pawl 37 and the locking pawl 66 operates as an escapement mechanism to control the movement of the ratchet gear 31.

A spring 69, one end of which is affixed to an abutment 68 of the locking pawl housing 64, is connected to the pawl actuator 33 (as shown in FIGURE 2). The spring 69 serves to retain the pawl actuator 33 in the position shown in FIGURES 3 and 6 (again, the full line position shown in FIGURE 3). An adjusting bolt 70 passes through the locking pawl housing 64 such that an end thereof is disposed adjacent the advancing pawl 37. As hereinafter described, the positioning of the adjustment bolt 70 provides adjustable means for preventing the advancing pawl 37 from overdriving the ratchet gear 31 by arresting the movement of the said pawl 37 at a given predetermined position on the return stroke of the mechanism.

A shaft 71 is mounted between the intermediate wall 12 and the side wall 13 in parallel alignment and beneath the shaft 30. Cam stop members 72 and 73 are mounted for rotation on the shaft 71, and are retained in a predetermined position by retaining rings generally designated by the reference letter R'. Cam flanges 74 and 75 extend respectively from the cam stop members 72 and 73 towards the solenoids 56 and 57. Stop portions 76 and 77 extend respectively from the cam stop members 72 and 73 in the opposite direction. The stop portions 76 and 77 are provided with extending abutment shoulders 82 and

83, respectively. Return springs 78 and 79 normally bias the cam stop members 72 and 73 to the positions shown in FIGURES 3 and 6 (again, the full line position in FIGURE 3). A U-shaped support plate 80, which is affixed to the base plate 10, is disposed beneath the stop portions 76 and 77 of the respective cam stop members 72 and 73 such that the springs 78 and 79 normally bias these members into a rest position atop the said plate 80.

A limit bar 81 (fragments of which are shown in FIGURE 5) is positioned between the intermediate wall 12 and the side wall 13 between the switch mounting plate 8 and the shaft 71. As hereinafter described, the bar 81 serves to limit the movement of the pawl actuator 33 in order to determine a movement of the ratchet gear 31 corresponding to a half-dollar cumulation in the counter barrel assembly 26.

In operation, the income totalizing device 1 will normally assume the positions shown in FIGURES 1, 2, and 4-6, as well as the positions shown in full lines in FIGURE 3, by virtue of the various spring interconnections previously described. When a nickel signal is received (i.e., momentary energization of the nickel solenoid 54), the plunger 54P will be retracted such that the nickel lever 46 will rotate (clockwise in FIGURE 3). This actuation of the lever 46 will cause a corresponding rotation of the pawl actuator 33 as the lever 46 engages the lever arm 44 extending from the leg 34 of the pawl actuator 33. As the combined rotation continues, the extreme right hand portion of the lever 46 (relative to the FIGURE 3 disposition) will engage the cam flange 75 of the cam stop member 73, thereby rotating this member clockwise (relative to the FIGURE 3, disposition). The described rotation of the cam stop member 73 causes the shoulder 83 of the stop portion 77 to be disposed in the path of movement of the shoulder 41 of the pawl actuator 33, thereby impeding further movement thereof. Thus, energization of the nickel solenoid 54 effects a predetermined degree of movement for the pawl actuator 33.

As the pawl actuator 33 is thereby rotated by the said predetermined degree of movement, the advancing pawl 37, which is carried by the pawl actuator 33, drags past the teeth of the ratchet gear 31 against the biasing force of the spring 38. When the movement of the pawl actuator 33 is arrested, the advancing pawl 37 is urged into engagement with the teeth of the ratchet gear 31 by the spring 38. When the nickel solenoid 54 is de-energized, the springs 62, 69, and 79 respectively return the nickel lever 46, the pawl actuator 33, and the cam stop member 73 to their respective normal rest dispositions. As the pawl actuator 33 thus returns to its original disposition, the advancing pawl 37 causes a counter-clockwise (relative to the FIGURE 3 disposition) rotation of the ratchet gear 31. The ratchet gear and correspondingly the spur gear 32 and the intermeshed pinion gear 25 are thus rotated by an amount corresponding to the amount of arcuate movement of the nickel lever 46, since the said lever retraces this amount in its return to its original disposition. The ratchet gear 31 drags against the locking pawl 66 as it thus rotates, and the pawl 66 is urged into engagement with the teeth of the ratchet gear 31 by the spring 67 in order to prevent backlash movement of the ratchet gear 31.

Thus, the advancing pawl 37 and the locking pawl 66 act as an escapement mechanism to control the rotation of the ratchet gear 31 to a predetermined extent. The adjusting bolt 70, the exposed end of which is disposed in the path of the advancing pawl 37, serves to lock the advancing pawl 37 in the teeth of the ratchet gear 31 at a predetermined location, thereby to prevent overdriving of the ratchet gear 31. The disposition of the adjustment bolt 70 relative to the ratchet gear 31 determines the original disposition of the advancing pawl 37 (and therefore of the pawl actuator 33), since the spring 69 will bias the pawl actuator 33 such that the advancing pawl 37

is impeded by the end of the adjusting bolt 70 and is thereby cammed into locking engagement with the teeth of the ratchet gear 31. While the income totalizing device 1 is calibrated by the inherent dimensions of its respective components so as to effectuate a rotation of the pinion gear 25, it is apparent that the adjusting bolt 70 may be utilized for fine calibration of one or two units of revolution corresponding to the arcute length of a tooth segment of the ratchet gear 31.

When a dime signal is sensed by the income totalizing device 1 (i.e., momentary energization of the dime solenoid 55), a corresponding series of events is observed. In this instance, the dime lever 47 (see FIGURE 6) is caused to rotate counter-clockwise (relative to the FIGURE 6 disposition) and to engage the lever arm 45 extending from the leg 35 of the pawl actuator 33. The dime lever 47 continues to advance while pushing the pawl actuator 33 until the extreme tip of the lever 47 engages the cam flange 74 of the cam stop member 72, thereby causing this member to rotate counterclockwise (relative to the FIGURE 6 disposition). This rotation continues until the shoulder 39 of the pawl actuator 33 is impeded by the shoulder 82 of the cam stop member 72. Since the shoulder 39 is recessed relative to the shoulder 41, it is apparent that the pawl actuator 33 will be rotated by a greater extent than the amount of rotation induced by actuation of the nickel lever 46. In fact, the pawl actuator 33 is calibrated such that the offset between the shoulders 41 and 39 is sufficiently large so as to cause twice as much movement of the ratchet gear 31. In this manner, a ten cent registry is indicated by the counter barrel assembly 26, via the induced rotation of the pinion gear 25 intermeshing with the spur gear 32.

When a quarter signal is sensed by the income totalizing device 1 (i.e., momentary energization of the quarter solenoid 56), the quarter lever 48 causes the pawl actuator 33 to rotate in the same direction as did activation of the nickel lever 46. In this instance, however, the quarter lever 48 does not touch the cam stop member 72 until the shoulder 41 of the pawl actuator 33 has already rotated past the shoulder 83 of the cam stop member 73 (i.e., the extreme tip of the quarter lever 48 is disposed counter-clockwise from the extreme tip of the nickel lever 46, as best seen in FIGURE 3). When the quarter lever 48 does touch the cam flange 75, the shoulder 83 of the cam stop member 73 is disposed in the path of the shoulder 42 of the pawl actuator 33, and eventually movement of the pawl actuator 33 is impeded by interengagement of the shoulders 83 and 42. The amount of movement thus induced in the pawl actuator 33 is five times as great as the amount of movement induced in the pawl actuator 33 by actuation of the nickel lever 46, whereby return movement of the pawl actuator 33 causes the ratchet gear 31 to rotate five times as much as when the nickel lever 46 was actuated. In this manner, the counter barrel assembly 26 registers a twenty-five cent incremental change.

When a half-dollar signal is received in the income totalizing device 1 (i.e., momentary energization of the half-dollar solenoid 57), a slightly different operation is evidenced. For half-dollar registry, neither of the cam stop members 72 and 73 is utilized. Rather, the half-dollar lever 49 engages the lever arm 45 extending from the leg 35 of the pawl actuator 33 and causes rotation of the pawl actuator 33 completely past the cam stop members 72 and 73 until the shoulder 41 of the pawl actuator 33 engages the limit bar 81 disposed between the walls 12 and 13. Thus, the limit bar 81 serves the same functions as the shoulders 82 and 83 of the cam stop members 72 and 73 respectively in that a predetermined extent of movement of the pawl actuator 33 is determined by the positioning of the limit bar 81. In this manner, the ratchet gear 31 is induced to rotate by an amount ten times as great as the amount of rotation induced by actuation of the nickel lever 46 (via return of the pawl actuator 33). In

this manner, the counter barrel assembly 26 registers a fifty-cent incremental change.

While the description and operation herein has referred to a conventional nickel, dime, quarter, and half-dollar operation for United States currency coins, it should be understood that many variations are possible based upon the principles of the subject invention. For example, in certain instances, it may be desirable to cumulatively totalize successive signals of coin deposits for less than the four species of coins enumerated. To achieve this end, it is only necessary to disconnect or remove a given solenoid, either electrically or mechanically. Also, it may be desired to cumulatively totalize coin values of other species of coin denominations as, for example, pennies. To effectuate this end, it is only necessary to re-dimension the relative positioning of the extreme ends of the coin levers, of the cam stop members, and of the pawl actuator, in order to achieve the desired calibrated and predetermined extent of rotation for the ratchet gear 31. In practice, a simple substitution of parts could be utilized to effectuate the indicated conversions. It should also be understood that the income totalizing device 1 described herein can be readily adapted to the cumulative totalization of coin values of relative coin ratios other than the 1:2:5:10 ratio described for nickels, dimes, quarters, and half-dollars. For example, it may be desirable to calibrate the income totalizing device for the 1:2:5:10 relative coin ratios of the Netherlands-type coin systems or for the 1:2:4:8 relative coin ratios for the English-type coin systems.

Moreover, an income totalizing device of the general type described herein is readily adaptable to utilization for permanent recording (as by imprinting on a permanent data recording form, such as the form disclosed and claimed in a copending United States patent application entitled Data Recording Form Ser. No. 463,824, filed of even date herewith in the names of Albinus G. Bodoh and Jacob C. Kiefer and having the same assignee). This adaptation can be accomplished by substituting for the counter barrel assembly 26 a corresponding counter barrel assembly that provides exposable indicia die surfaces and by providing suitable mechanism for pressing the data recording form against exposed die surfaces in order to imprint totalization information on the form (such as the recording income totalizing arrangement described and claimed in a copending United States patent application entitled Income Totalizing Device and Method, Ser. No. 472,382, filed of even date herewith in the names of Herman G. Jensen and Joseph E. Wright, Jr. and having the same assignee).

It should also be understood that various other changes and modifications may be effected in the details of construction and arrangements of the various elements, without departing from the spirit and scope of the instant invention, as defined in the appended claims.

What is claimed is:

1. An income totalizing device for totalizing in incremental amounts the cumulative value of coins deposited in a coin-receiving mechanism comprising:

a shaft; 60
a first rotatable member mounted on the shaft; a second rotatable member mounted on the shaft; means normally retaining the said members in a given

relative angular orientation;

coin signal means selectively responsive to the denomination of a coin deposited in the coin receiving mechanism;

means responsive to the coin signal means for rotating the first rotatable member relative to the second rotatable member by a predetermined angular increment in a given direction;

a plurality of independent stop means, each of the stop means being adapted to engage the first rotatable member to limit the extent of rotation thereof to the said angular increment, and each of the stop means 75

being adapted to function separately of the other stop means;

means responsive to deviation of the said members from the said orientation for reversely rotating both the first rotatable member and the second rotatable member by the said angular increment; and means responsive to rotation of the second rotatable member for indicating the value of the deposited coin.

2. An income totalizing device as claimed in claim 1 wherein each of the stop means corresponds to a particular coin denomination and comprises an individual stop member located adjacent the first rotatable member and adapted to engage a corresponding individual shoulder portion located on the first rotatable member.

3. A device for totalizing in incremental amounts the cumulative value of coins having respective coin denominations of C_1 and C_2 , which comprises:

a shaft; a first rotatable member mounted on the shaft; a second rotatable member mounted on the shaft; means normally retaining the said members in a given relative angular orientation; coin signal means responsive to the said coin denominations;

means responsive to the coin signal means for rotating the first rotatable member relative to the second rotatable member by D° in a given direction from the said orientation;

a plurality of independent stop means, each of the stop means being adapted to engage the first rotatable member to limit the extent of rotation thereof to D° , and each of the stop means being adapted to function separately of the other stop means;

means responsive to deviation of the said members from the said orientation for reversely rotating both the first rotatable member and the second rotatable member by D° ; and

means responsive to rotation of the second rotatable member for indicating the coin values, where D equals a given angular incremental amount and (C_2/C_1) times the said incremental amount for the respective C_1 and C_2 signaled denominations.

4. A device for totalizing cumulative income values comprising:

a frame; rotatable actuator means; rotatable ratchet means;

means normally retaining the said rotatable actuator and ratchet means in respective given initial dispositions;

credit signal means adapted to be actuated in selective response to the value of an income increment to be credited;

means responsive to the credit signal means for effecting reciprocal rotation of the rotatable actuator means away from and back to its initial disposition;

a plurality of independent stop means, each of the stop means being adapted to engage the rotatable actuator means to limit the extent of rotation thereof to an amount representative of a particular income value associated with the particular stop means, and each of the stop means being adapted to function separately of the other stop means in response to crediting of the particular income value associated therewith;

driving pawl means responsive to rotation of the rotatable actuator means in one of its directions of rotation for effecting rotation of the rotatable ratchet means away from its initial disposition in the same direction and to the same extent as the rotation of the rotatable actuator means; and

means responsive to the extent of rotation of the rotatable ratchet means for indicating the signaled income value.

5. A device for cumulatively totalizing in incremental amounts the value of coins of a first C_1 and of a second C_2 denomination which are deposited in a coin-receiving mechanism, which comprises:

a housing;

a shaft fixedly positioned in the housing;

a ratchet gear means rotatably mounted on the shaft; first C_1 denomination crank means rotatably journaled on the shaft and normally biased to a given rest position;

second C_2 denomination crank means rotatably journaled on the shaft and normally biased to a given rest position;

first solenoid actuated means responsive to the deposit of a C_1 coin for effecting rotation of the first crank means from its given rest position;

second solenoid actuated means responsive to the deposit of a C_2 coin for effecting rotation of the second crank means from its given rest position;

advancing pawl means responsive to rotation of either of the crank means for rotating the ratchet gear means by a given amount when the first crank means is rotated and by an amount (C_2/C_1) times as great as the said given amount when the second crank means is rotated;

first stop means normally stationed in an inoperative position and operatively responsive to the deposit of a C_1 coin to move to an operative position to engage the advancing pawl means and thereby limit the rotation of the ratchet gear to the said given amount;

second stop means normally stationed in an inoperative position and operatively responsive to the deposit of a C_2 coin to move to an operative position to engage the advancing pawl means and thereby limit the rotation of the ratchet gear means to an amount (C_2/C_1) times as great as the said given amount, the first stop means remaining in its normal inoperative position during operation of the second stop means and the second stop means remaining in its normal inoperative position during operation of the first stop means; and

gear registry means responsive to rotation of the ratchet gear means for cumulatively totalizing in incremental amounts either the C_1 or C_2 coin denominations.

6. A device as claimed in claim 5 wherein the said advancing pawl means comprises:

a pawl actuator mounted for rotation on the shaft; a spring biased advancing pawl carried by the pawl actuator and normally urged into engagement with the teeth of the ratchet gear means;

a first and a second lever portion extending from the pawl actuator in the respective paths of movement of the first and the second crank means; and

a driving spring connected to the housing and to the pawl actuator and normally urging the pawl actuator into a given rest position relative to the shaft,

whereby rotation of either of the first and the second crank means effects a corresponding rotation of the pawl actuator against the force of the driving spring so that the driving spring may return the pawl actuator to the said rest position, thereby driving the ratchet gear means on the return movement of the pawl actuator.

7. A device as claimed in claim 6 wherein each of the first and second stop means comprises an individual stop member located adjacent the pawl actuator and adapted to engage a corresponding individual shoulder portion located on the pawl actuator.

8. A device as claimed in claim 7 wherein the stop members of the first and second stop means are adjustable in response to contact with the first C_1 crank means and the second C_2 crank means respectively.

9. A device for cumulatively totalizing the incremental

10

amounts the value of nickels, dimes, quarters, and half-dollars which are deposited in a coin-receiving mechanism which comprises:

a housing;

a shaft fixedly positioned in the housing;

a ratchet gear means rotatably mounted on the shaft; nickel, dime, quarter, and half-dollar crank means rotatably journaled on the shaft and each normally biased to a given rest position;

nickel, dime, quarter, and half-dollar solenoid actuated means responsive to the deposit of nickels, dimes, quarters, and half-dollars respectively for effecting rotation of the corresponding crank means from the respective rest positions;

advancing pawl means responsive to rotation of any one of the crank means for rotating the ratchet gear means by a given amount; twice the said given amount; five times the said given amount; and ten times the said given amount when the respective nickel, dime, quarter, and half-dollar crank means are rotated by the corresponding solenoid actuated means;

independent nickel, dime, quarter, and half-dollar stop members mounted in the housing adjacent the advancing pawl means;

nickel, dime, quarter, and half-dollar shoulder portions located on the advancing pawl means for cooperation respectively with the nickel, dime, quarter, and half-dollar stop members, each combination of a stop member and its associated shoulder portion being adapted to function separately of the other combinations of a stop member and an associated shoulder portion; and

gear registry means responsive to rotation of the ratchet gear means for cumulatively totalizing in incremental amounts either the nickel, dime, quarter, or half-dollar denominations.

10. A device as claimed in claim 9 wherein the stop members of the nickel, dime, and quarter stop means are independently adjustable respectively in response to rotation of the nickel, dime, and quarter crank means to limit the extent of rotation of the advancing pawl means to an amount corresponding to the value accorded to the income increments represented by the associated coins.

11. A device for cumulatively totalizing in incremental amounts the values of nickels, dimes, quarters, and half-dollars which are deposited in a coin-receiving mechanism, which comprises:

a housing;

a shaft fixedly positioned in the housing;

a ratchet gear rotatably mounted on the shaft;

a nickel, a dime, a quarter, and a half-dollar crank lever, each rotatably mounted on the shaft and each being spring biased to a given rest position;

nickel, dime, quarter, and half-dollar solenoid means for rotating each of the respective crank levers away from their respective given rest positions;

a pawl actuator rotatably mounted on the shaft and spring biased to a given rest position;

an advancing pawl carried by the pawl actuator and adapted to engage the teeth of the ratchet gear;

lever means carried by the pawl actuator and extending in the respective paths of movement of the crank levers;

stop means comprising nickel, dime, quarter, and half-dollar stop members mounted in the housing and adapted to engage respectively nickel, dime, quarter, and half-dollar shoulder portions on the pawl actuator for arresting the respective movements of the nickel, dime, quarter, and half-dollar crank levers

after any one of the said crank levers has rotated the pawl actuator by a given amount; twice the said given amount; five times the said given amount; or ten times the said given amount respectively; the nickel, dime, and quarter stop members each includ-

ing a cam flange to be engaged by an actuating tip on the corresponding crank lever to cam the respective stop member to an operative position, and the half-dollar stop member being an immovable bar; and

5 counter gear means controlled by the extent of rotation of the ratchet gear, whereby energization of the respective nickel, dime, quarter, and half-dollar solenoid means actuates the corresponding crank lever so as to reciprocate the pawl actuator through a predetermined extent of rotation and thereby to rotate the ratchet gear by a corresponding extent.

12. A device for cumulatively totalizing in incremental amounts the values of nickels, dimes, quarters, and half-dollars which are deposited in a coin-receiving mechanism, which comprises:

a housing;

a first shaft fixedly positioned in the housing;

a ratchet gear rotatably mounted on the first shaft;

a nickel, a dime, a quarter, and a half-dollar crank lever, each rotatably mounted on the first shaft and each being spring biased to a given rest position;

15 nickel, dime, quarter, and half-dollar relay means for rotating each of the respective crank levers away from their respective given rest positions;

a pawl actuator rotatably mounted on the first shaft and spring biased to a given rest position;

20 an advancing pawl carried by the pawl actuator and adapted to engage the teeth of the ratchet gear;

lever means carried by the pawl actuator and extending in the respective paths of movement of the crank levers;

25 a second shaft fixedly positioned in the housing;

a first cam stop member rotatably mounted on the second shaft and adapted for actuation by rotation of the nickel crank lever to arrest the movement thereof after the nickel crank lever has rotated the pawl actuator by a given amount and for actuation by rotation of the quarter crank lever to arrest the movement thereof after the quarter crank lever has rotated the pawl actuator by five times the said amount;

30 a second cam stop member rotatably mounted on the second shaft and adapted for actuation by rotation of the dime crank lever to arrest the movement thereof after the dime crank lever has rotated the pawl actuator by twice the said amount;

a limit bar fixedly positioned in the housing to arrest the movement of the half-dollar crank lever after the half-dollar crank lever has rotated the pawl actuator by ten times the said amount; and

35 counter gear means controlled by the extent of rotation of the ratchet gear,

whereby energization of the respective nickel, dime, quarter, and half-dollar relay means actuates the corresponding crank lever so as to reciprocate the pawl actuator through a predetermined extent of rotation and thereby to rotate the ratchet gear by a corresponding extent.

13. A device for cumulatively totalizing in incremental amounts the values of nickels, dimes, quarters, and half-dollars which are deposited in a coin-receiving mechanism, which comprises:

a housing;

a shaft fixedly positioned in the housing;

60 a ratchet gear rotatably mounted on the shaft;

a nickel, a dime, a quarter, and a half-dollar crank lever, each parallelly mounted on the shaft for rotation with respect thereto and each being normally retained in a given rest position;

65 nickel, dime, quarter, and half-dollar solenoid means; means responsive to actuation of said solenoid means for effecting rotation of each of the corresponding crank levers away from its respective given rest position;

a pawl actuator rotatably mounted on the shaft and biased to a given rest position;

advancing pawl means adapted to engage the teeth of the ratchet gear;

means carried by the pawl actuator and extending in the respective paths of movement of the crank levers to engage the respective crank levers and thereby cause rotation of the pawl actuator;

independent nickel, dime, quarter, and half-dollar stop means for limiting the respective rotatable movements of the nickel, dime, quarter, and half-dollar crank levers to a given amount; twice the said given amount; five times the said given amount; or ten times the said given amount, respectively, the nickel, dime, and quarter stop means comprising adjustable stop members mounted in the housing and adapted to engage corresponding respective shoulder portions on the pawl actuator, and the half-dollar stop means comprising a fixed stop member adapted to engage a corresponding shoulder on the pawl actuator;

means for reciprocally rotating the pawl actuator to and from its given rest position; and

counter gear means controlled by the extent of rotation of the ratchet gear,

whereby upon energization of the respective nickel, dime, quarter, and half-dollar solenoid means the corresponding crank lever is actuated such that reciprocation of the pawl actuator through its predetermined extent of rotation can serve to effect rotation of the ratchet gear by a corresponding extent.

14. A device for totalizing cumulative income values comprising:

a frame;

rotatable actuator means;

rotatable ratchet means;

means normally retaining the said rotatable actuator and ratchet means in respective given initial dispositions;

credit signal means adapted to be actuated in selective response to the value of an income increment to be credited;

means responsive to the credit signal means for effecting reciprocal rotation of the rotatable actuator means away from and back to its initial disposition; a plurality of independent stop means limiting the extent of rotation of the rotatable actuator means to an amount corresponding to the income value signaled by the credit signal means, each of the stop means comprising a stop member mounted in the frame and adapted to engage a corresponding shoulder portion located on the rotatable actuator means, and each of the stop means being adapted to function separately of the other stop means;

driving pawl means responsive to rotation of the rotatable actuator means in its direction of rotation back to its initial disposition for effecting rotation of the rotatable ratchet means away from its initial disposition in the same direction and to the same extent as the rotation of the rotatable actuator means in its direction of rotation back to its initial disposition; and

means responsive to the extent of rotation of the rotatable ratchet means for indicating the signaled income value.

15. An income totalizing device for totalizing in incremental amounts the cumulative value of coins deposited in a coin-receiving mechanism comprising:

a shaft;

a first rotatable member mounted on the shaft;

a second rotatable member mounted on the shaft;

means normally retaining the said members in a given relative angular orientation;

coin signal means selectively responsive to the denominations;

13

nation of a coin deposited in the coin-receiving mechanism;
 crank means responsive to the coin signal means for rotating the first rotatable member relative to the second rotatable member by a predetermined angular increment in a given direction;
 stop means comprising an adjustable stop member located adjacent the first rotatable member and adapted to engage a corresponding shoulder portion located on the first rotatable member to thereby limit the extent of rotation of the first rotatable member to the said angular increment, the stop member being actuated by the crank means during rotation of the first rotatable member with respect to the second rotatable member;
 means responsive to deviation of the said members from the said orientation for reversely rotating both the first rotatable member and the second rotatable member by the said angular increment; and
 means responsive to rotation of the second rotatable member for indicating the value of the deposited coin.

16. A device for totalizing cumulative income values comprising:

a frame;
 rotatable actuator means;
 rotatable ratchet means;
 means normally retaining the said rotatable actuator and ratchet means in respective given initial dispositions;
 credit signal means adapted to be actuated in selective response to the value of an income increment to be credited;
 means responsive to the credit signal means for effecting reciprocal rotation of the rotatable actuator means away from and back to its initial disposition;
 a plurality of adjustable independent stop means, each stop means comprising an adjustable stop member located adjacent the rotatable actuator means and adapted to engage a corresponding shoulder portion

located on the rotatable actuator, and each stop means being independently responsive to a particular predetermined income increment to limit the extent of rotation of the rotatable actuator to an amount corresponding to the value accorded to the said predetermined income increment;

driving pawl means responsive to rotation of the rotatable actuator means in one of its directions of rotation for effecting rotation of the rotatable ratchet means away from its initial disposition in the same direction and to the same extent as the rotation of the rotatable actuator means; and

means responsive to the extent of rotation of the rotatable ratchet means for indicating the signaled income value.

17. A device as claimed in claim 16 wherein the means responsive to the credit signal means comprises a plurality of crank means each individually responsive to a particular income increment to engage the rotatable actuator and rotate it an amount corresponding to the income value associated with the said particular income increment; and each crank means contacts a cam flange on a corresponding adjustable stop means to cause the said stop means to engage the rotatable actuator means and limit the extent of rotation thereof.
